US0D1033423S

(12) **United States Design Patent** (10) Patent No.: **US D1,033,423 S**
(45) Date of Patent: ** *Jul. 2, 2024

(54) **FOLDABLE ELECTRONIC DEVICE WITH DUAL DISPLAY SCREENS**

(71) Applicant: **COMPAL ELECTRONICS, INC.**,
Taipei (TW)

(72) Inventors: **Jyh-Chyang Tzou**, Taipei (TW);
Han-Tsai Liu, Taipei (TW)

(73) Assignee: **COMPAL ELECTRONICS, INC.**,
Taipei (TW)

(*) Notice: This patent is subject to a terminal disclaimer.

(**) Term: **15 Years**

(21) Appl. No.: **29/737,382**

(22) Filed: **Jun. 9, 2020**

(30) **Foreign Application Priority Data**

May 6, 2020 (TW) 109302412

(51) **LOC (14) Cl.** **14-02**

(52) **U.S. Cl.**

USPC **D14/315**

(58) **Field of Classification Search**
